UNITED STATES PATENT OFFICE.

MONROE LE VINO, OF NEW YORK, N. Y.

BOOK-HOLDER.

1,217,024.

Specification of Letters Patent. Patented Feb. 20, 1917.

Application filed February 19, 1915. Serial No. 9,274.

To all whom it may concern:

Be it known that I, MONROE LE VINO, a citizen of the United States, and a resident of the city of New York, borough of Manhattan, in the county and State of New York, have invented a new and Improved Book-Holder, of which the following is a full, clear, and exact description.

The object of the invention is to provide a new and improved bookholder more especially designed for use on desks for holding the telephone directory, reference book or other book within convenient reach of the user of the desk, and to allow the user to move the book into position for use without detaching it from the bookholder.

In order to accomplish the desired result, use is made of a frame mounted to swing on a bracket attached to a desk or other support, a pivot held on the upper rear corner of the frame for the book to swing on, and a rest movable on the front of the frame near the top thereof to close the frame at the front and to form a saddle or seat for the back of the book to rest on at the time the book is swung into position for use on the upper end of the frame.

A practical embodiment of the invention is represented in the accompanying drawings forming a part of this specification, in which similar characters of reference indicate corresponding parts in all the views.

Figure 1 is a perspective view of the bookholder in position on the desk with the book in position for use;

Fig. 2 is a side elevation of the book holder with the book shown in full lines when not in use and in dotted lines when in use;

Fig. 3 is an enlarged sectional plan view of part of the frame and the pivot for the book, the section being on the line 3-3 of Fig. 2;

Fig. 4 is a similar view of the front portion of the frame at the saddle, the section being on the line 4-4 of Fig. 2;

Fig. 5 is an enlarged sectional plan view of the pivotal end of the frame and the bracket for the same;

Fig. 6 is a sectional plan view of the bookholder on the line 6-6 of Fig. 2; and

Fig. 7 is an enlarged side elevation of the upper rear corner of one of the side pieces.

The bookholder consists essentially of a frame formed of two side pieces A and A'

preferably made of wire bent into rectangular shape. The bottom bars B, B' of the side pieces A, A' are connected with each other intermediate their ends by a U-shaped cross piece B², and the lower ends of the rear bars C, C' of the side pieces terminate in converging arms C², C³, attached to or formed into a vertically disposed pivot C⁴ seated in a socket D' of a bracket D secured to a desk E or other suitable support. The bracket D is preferably located at one corner of the desk E to permit of conveniently swinging the bookholder from one side of the desk to a front position whenever it is desired to use the book for reference or other purposes. It will be noticed that the connection B² as well as the converging arms C², C³ permit of being bent to move the side pieces A and A' nearer together or farther apart according to the thickness of the book F to be held between the side pieces of the frame.

The book F is provided with a transverse aperture adjacent the back near the upper end and through this opening extends a pivot G held in eyes H, H' formed by bending the adjacent ends of the bars C, C' and the top bars I, I' correspondingly, as will be readily understood by reference to Figs. 1, 2, 3 and 7. By the arrangement described the book F is mounted to swing on the pivot G and when the book is in normal position its bottom rests on the connection B². The eyes H, H' are elongated and normally closed to hold the pivot G in place but the eyes may be opened by inserting a tool between the shanks of the eyes and prying the shanks apart to allow of disengaging the pivot G from the eyes whenever it is desired to remove the book from the holder or replace it thereon without first removing the pivot G from the book. The pivot G is preferably in the form of a rod provided at one end with a nut or head G' and terminating at the other end in a coil G² having one or more convolutions to allow of unbending and straightening part of the coil for lengthening the pivot G whenever the side pieces A, A' are moved apart for accommodating a thicker book as previously explained.

When it is desired to use the book, it is swung upward on the pivot G into the position shown in Fig. 1, the forward end of the back of the book then resting on the saddle J in the form of a cross bar having 110

one end formed into an eye engaging a bent portion K' formed in the front bar K of one of the side pieces of the frame, as shown, the side piece A . The free end of the saddle 5 J terminates in a coil J^2 forming a catch adapted to engage the front bar K^2 of the other side piece A' . The coil J^2 is provided with one or more convolutions similar to the coil G^2 above described to allow of 10 lengthening the saddle J whenever the side pieces A, A' are moved farther apart. When the book F is in normal lowermost position the saddle J is in closed position and connects the front bars K', K^2 with each 15 other and thus extending across the front of the book F to hold the latter against movement while at rest between the side pieces A, A' . When it is desired to swing the book F into uppermost position, the 20 operator first disengages the coil J^2 from the bar K^2 and swings the saddle J into open position, after which the book F is swung upward until the back is above the saddle J , and then the latter is swung back 25 into closed position to allow the back of the book to rest on the saddle J , as shown in Fig. 1 and indicated in dotted lines in Fig. 2.

The bookholder shown and described is 30 very simple and durable in construction and can be very cheaply manufactured and readily applied to a desk or other support. It is understood that the book F can be readily placed between the side pieces A, A' 35 and engaged with the pivot G to allow of swinging the book from normal lowermost position into uppermost position for use of the occupant of the desk. It will be noticed that when the book F is in position for use 40 its back is securely held between the upper portions of the side pieces A, A' so that the book can be conveniently opened without danger of the book becoming disconnected from the holder or requiring the 45 operator to hold the book while using it.

Having thus described my invention, I claim as new and desire to secure by Letters Patent:

1. A bookholder, comprising a bracket 50 adapted to be secured to a support, an upright frame mounted to swing on the said bracket, a pivot held on the upper rear corner of the frame and adapted to extend transversely through the back of a book to 55 hold the latter in the frame, and a rest held on the front of the frame a distance below the top thereof to close the frame and to form a support for the book when the latter is swung upward into position for use.

60 2. A bookholder, comprising a frame having side pieces, the bottom connections connecting the side frames with each other at the bottom, a transverse pivot connecting the side frames with each other at the upper rear corner, and a bar pivoted on the 65

front of one of the side pieces near the upper end thereof and adapted to engage the other side piece to connect the side pieces with each other at the front and to form a rest for the back of the book at the time 70 the book is in position for use.

3. A bookholder comprising a frame having side pieces, bottom connections connecting the side pieces with each other at the bottom, one of the bottom connections being 75 intermediate the ends of the side pieces and the other bottom connection being provided with a pivot pin, a transverse pivot connecting the side pieces with each other at the upper rear corner, a bar pivoted on the 80 front of one of the side pieces near the upper end thereof and adapted to engage the other side piece to connect the side pieces with each other at the front and to form a rest for the back of the book at the time 85 the book is in position for use, and a bracket adapted to be attached to a suitable support and engaged by the said pivot pin.

4. A bookholder provided with a frame 90 formed of two rectangular side pieces made of wire, and an approximately U-shaped crosspiece rigidly attached at its ends to the bottom bars of the side pieces intermediate their ends, the said crosspiece extending in the plane of the said bottom bars and being 95 capable of being bent to space the said side frames nearer together or farther apart according to the thickness of the book to be held between the said side pieces.

5. A bookholder provided with a frame 100 having two rectangular side pieces made of wire and between which the book is to be held, a bent connecting bar connecting the bottom bars of the side pieces with each other intermediate the front and back, a 105 pivot pin having upwardly extending and sidewise diverging bars connected with the said bottom bars at the rear end thereof, and a pivot connecting the rear upper corners of the side pieces with each other.

6. A bookholder provided with a frame having two rectangular side pieces made of wire and between which an article is to be held, a U-shaped connecting bar connecting the bottom bars of the side pieces with each 115 other intermediate the front and back, a pivot pin having upwardly extending and sidewise diverging bars connected with the said bottom bars at the rear end thereof, a pivot connecting the rear upper corners of 120 the side pieces with each other, and a resting and connecting bar pivoted on the front bar of one of the side pieces and terminating in a catch adapted to engage the front bar of the other side piece.

7. A bookholder provided with a frame having two rectangular side pieces made of wire and between which a book is to be held, the upper back corners of the side pieces being bent to form eyes, a pivot en- 130

gaging the said eyes, and connections connecting the bottom bars of the side pieces with each other.

8. A bookholder provided with a frame 5 having two rectangular side pieces made of wire and between which a book is to be held, the upper back corners of the side pieces being bent to form eyes and the front bar of one of the side pieces being provided near 10 its upper end with a bend, a pivot engaging the said eyes, a connecting bar having an eye at one end engaging the said bend, the free end of the connecting bar terminating in a catch adapted to engage the front bar 15 of the other side piece, and bottom connections connecting the bottom bars of the side frames with each other.
9. A bookholder provided with a frame 20 formed of two rectangular side pieces made of wire, the bottom bars of the side pieces being connected with each other by members capable of being bent to space the side frames nearer together or farther apart according to the thickness of the book to be 25 held between the said side pieces, a pivot connecting the upper rear corners of the side pieces with each other, the pivot having a coil to permit of lengthening the pivot, and a saddle mounted to swing on the front member of one of the side pieces and terminating 30 in a coil adapted to engage the front member of the other side piece, the said saddle

idle coil permitting of lengthening the saddle.

10. A bookholder provided with a frame 35 provided with two side pieces made of wire bent to provide elongated eyes adapted to open or close, and a pivot removably engaging the said eyes and adapted to pass through a book held between the said side 40 pieces.

11. A bookholder provided with a frame having side pieces adapted to be moved toward or from each other, and a pivot connecting the said side pieces with each other 45 and having a coil to permit of lengthening the pivot.

12. A bookholder provided with a frame having side pieces adapted to be moved toward or from each other, an adjustable pivot 50 adapted to pass through a book and connecting the said side pieces with each other, and a saddle pivoted at one side piece and terminating in a coil forming a catch adapted to engage the other side piece, the said coil 55 permitting of lengthening the saddle.

In testimony whereof I have signed my name to this specification in the presence of two subscribing witnesses.

MONROE LE VINO.
